SVEN WENNERG, OF SÖDERTELJE, SWEDEN, ASSIGNEE TO THE DE LAVAL
SEPARATOR COMPANY, OF NEW YORK, N. Y.

CENTRAL FEED-PIPE FOR CENTRIFUGAL BOWLS.

1,064,572.

Specification of Letters Patent. Patented June 10, 1913.

Application filed September 30, 1912. Serial No. 723,045.

To all whom it may concern:

Be it known that I, SVEN WENNERG, a subject of the King of Sweden, residing at 33 Storgatan, Södertelje, in the Kingdom of

Sweden, have invented certain new and useful Improvements in Central Feed-Pipes for Centrifugal Bowls, of which the following is a specification.

This invention relates to an improvement 10 in such central feed pipes for centrifugal bowls, which are cast in one piece with the under part or bottom of the bowl said latter part being provided with a central bore for the upper end of the driving shaft and with 15 channels departing from the upper part of the central feed pipe and ending in the separating chamber beneath the liner.

The invention is illustrated in the accompanying drawing showing in vertical section 20 the feed device and the under part or bottom of the bowl combined therewith.

a is the bottom part of the bowl and *b* is the central feed pipe cast in one piece with the bottom part. The said bottom part is 25 provided with a central bore for the driving shaft (this latter not shown on the drawing). In the walls of the bottom part and the central feed pipe there are cut vertical grooves *c*, which at their lower end are 30 curved outwardly, so that they open at the upper and outer border of the bottom part. The grooves *c* communicate at their upper ends with the interior of the central feed pipe through openings *d* in the wall of the 35 said pipe. Furthermore there is a cylindrical sleeve *e* turned over and fitting closely to the central pipe, said sleeve being curved outwardly after about the same radius as the grooves in the bottom part of the bowl. 40 The length of the sleeve is thus adjusted that when placed on the pipe the outer parts of the grooves *c* are left free. By this arrangement there is thus formed closed passages 45 through which the liquid to be separated is conducted from the interior of the central feed pipe, passing at the side of the upper end of the spindle, to the lower part of the separating chamber. It will be observed that by this arrangement, notwithstanding 50 the upper end of the spindle being drawn up to a certain height in the bowl, the distributing organ does not itself take up any room in radial direction, but is limited to the dimension necessary with respect 55 to the fixed part surrounding the driv-

ing shaft. The sleeve *e* is provided with wings *f* entering corresponding cuts in the conical plates of the liner thus forming guides for the said plates.

Having now described and ascertained the 60 nature of my said invention and in what manner the same is to be performed I declare that what I claim is:—

1. In a centrifugal separator bowl having its bottom part cast in one piece with a central feed pipe, adapted to inclose the upper end of the driving shaft and in the upper part of which the liquid to be separated is introduced, a number of downwardly extending grooves formed in the walls of the 70 feed pipe and the bottom part of the bowl and communicating with the interior of the central feed pipe, said grooves being curved outwardly, and a sleeve fitting closely to the central feed pipe and closing said grooves 75 outwardly leaving their outer ends free.

2. In a centrifugal separator bowl having its bottom part cast in one piece with a central feed pipe adapted to inclose the upper 80 end of the driving shaft and in the upper part of which the liquid to be separated is introduced, a number of downwardly extending grooves formed in the walls of the feed pipe and the bottom part of the bowl 85 and communicating with the interior of the central feed pipe, said grooves being curved outwardly, and a sleeve fitting closely to the central feed pipe and closing said grooves 90 outwardly leaving their outer ends free, and a number of vertical wings on the wall 95 of the said sleeve forming guides for the conical plates of the liner.

3. In a centrifugal separator, a bowl having a bottom part and a central feed pipe constituting a continuation thereof and 95 adapted to inclose the upper end of the driving shaft and in the upper part of which the liquid to be separated is introduced, there being a number of downwardly extending milk-conveying grooves formed in the walls 100 of the feed pipe and the bottom part of the bowl and communicating with the interior of the central feed pipe, the lower or exit ends of which extend outwardly and open into the lower part of the bowl, and a sleeve fitting the central feed pipe and closing said 105 grooves outwardly except at their lower or exit ends.

4. In a centrifugal separator, a bowl having a bottom part and a central feed pipe con- 110

stituting a continuation thereof and adapted to inclose the upper end of the driving shaft and in the upper part of which the liquid to be separated is introduced, there being a number of downwardly extending milk-conveying grooves formed in the walls of the feed pipe and the bottom part of the bowl and communicating with the interior of the central feed pipe, the lower or exit ends of which extend outwardly and open into the lower part of the bowl, a sleeve fitting the

central feed pipe and closing said grooves outwardly except at their lower or exit ends, and a number of vertically extending wings on the walls of said sleeve forming guides for the conical plates of the liner.

In testimony whereof I have affixed my signature in presence of two witnesses.

SVEN WENNERBERG.
